Term of patent 14 years

(Cl. D48—31)

FIG. 2

FIG. 1

FIG. 1 is a front elevation of a lighting fixture, showing my new design, with the standard broken away in part to indicate indeterminate length. The sides of the lighting fixture not shown are substantially like the sides shown, each side being at right angles to the other;

FIG. 2 is a top plan view thereof.

The dominant features of my design reside in the full line portions of the drawings.

I claim:

The ornamental design for a lighting fixture, substantially as shown and described.
